VENETIAN BLIND CONSTRUCTION

Edward E. Schaefer, Oak Park, Ill., assignor to
 Edward E. Schaefer, Alvin A. Steinert, Arthur
 A. Zucker, and George J. Halper, a copartner-
 ship doing business as Acme Venetian Blind
 Company, Chicago, Ill.

Application October 17, 1947, Serial No. 780,599

4 Claims. (Cl. 160—173)

1

This invention relates to an improved Venetian blind construction and more particularly to a novel means for detachably fastening the raising and lowering cords to the blind.

In the conventional Venetian blind a horizontal tilting rail is provided having secured thereto a plurality of depending ladder tapes each of which comprises a pair of front and rear parallel tapes connected at intervals by cross-linking rungs. Horizontal slats are supported one above the other by the rungs of the ladder tapes, and the tapes are fastened at their lower ends to a horizontal bottom rail. A tilting mechanism is operatively connected to the titling rail for opening and closing the slats of the blind. Operating cords for raising and lowering the blind extend downwardly from the titling rail through a series of aligned openings in the slats and are secured to the bottom rail.

The great inconvenience encountered in the cleaning of the conventional Venetian blind has long been recognized as a major problem in the maintenance and care of Venetian blinds. Because the raising and lowering cords passed vertically through the slats it was impossible to withdraw the slats laterally from the ladder tapes until the cords had first been removed. Such cord removal was accomplished only with difficulty because the cords themselves were secured either by knots or by nails or other like means which prevented ready detachment. The inconvenience and difficulty were so great that considerable development work has been directed toward a blind in which the cords do not pass through the slats but are disposed at the outer edges thereof. However, most of the proposed structures have proved unsatisfactory in practice either because the slats are not held securely enough to the ladder tapes and are prone to undergo unsightly lateral displacement, or because the method of attachment of the slats involves complex and inconvenient fastening devices such as clips, hooks, etc.

In the Venetian blind construction of the present invention the slats are of the conventional slotted type but are rendered readily removable by the provision of a novel and simple device for detaching the raising and lowering cords from the blind. Obviously, once the cords are detached, they can be pulled through the openings in the slats and the slats may then be removed laterally from the supporting rungs of the ladder tapes. The present invention is an improvement over the cord fastening device disclosed in my earlier Patent No. 2,314,461, issued March 23, 1943.

2

Accordingly the principal object of the present invention is to provide a Venetian blind construction in which the raising and lowering cords are detachably secured to the blind and may be readily unfastened to permit removal of the slats.

A further object of the invention is to provide, in a Venetian blind, a novel detachable cord fastening and rail supporting device adapted to be permanently secured to the end of a raising and lowering cord.

An additional object of the invention is to provide, in a Venetian blind, a detachable cord fastening device for attachment to the end of a raising and lowering cord which also functions to secure the lower end of a ladder tape to the bottom rail of the blind.

A still further object of the invention is to provide, in a Venetian blind, a novel device for detachably fastening the end of a raising and lowering cord to the bottom rail of a Venetian blind, which device has in combination therewith a snap fastener structure adapted to secure the ladder tape to the bottom rail.

Other objects and advantages of the invention will become apparent upon reference to the accompanying drawings, in which:

Figure 1 is a front elevational view of an assembled two-tape Venetian blind showing the essential component parts thereof;

Fig. 2 is a fragmentary bottom plan view of a portion of the bottom rail of Fig. 1 showing the attachment of the ladder tapes thereto;

Fig. 3 is a sectional view taken along the line 3—3 of Fig. 2 looking in the direction of the arrows and showing in detail one form of the detachable cord fastening means comprising the present invention;

Fig. 4 is a front elevational view of an assembled four-tape Venetian blind embodying a modified form of detachable cord fastening means;

Fig. 5 is an enlarged perspective view of the form of detachable cord fastener shown in Fig. 4;

Fig. 6 is a fragmentary bottom plan view of a portion of the bottom rail of Fig. 4;

Fig. 7 is a sectional view taken along the line 7—7 of Fig. 6, looking in the direction of the arrows; and

Fig. 8 is a plan view of one of the elements of the device shown in Fig. 3.

In the assembled two-tape Venetian blind shown in Fig. 1, an upper housing or head rail 11 is provided, and pivotally mounted thereunder is a horizontal titling rail 12 connected to a titling mechanism 13 which is operable in the conventional manner by a cord 14 for titling the rail 12 forwardly or backwardly to open and close

the blind. Two depending ladder tapes 16 are fastened at their upper ends to the tilting rail 12 and are secured at their lower ends to a horizontal bottom rail 17. A plurality of horizontal slats 18 are supported by means of the transverse rungs (not shown) extending between the forward and rear tape members of each of the ladder tapes 16. Raising and lowering cords 19 extend downwardly from the head rail 11 through a plurality of aligned slotted openings (not shown) in the slats 18 and are detachably secured at their lower ends to the bottom rail 17 by means comprising the present invention and hereinafter described in greater detail.

In Figs. 2 and 3 one specific form of the detachable cord fastening device of the present invention is illustrated. To the end of the raising and lowering cord 19, and elongated, ferrule or tubular shank 21 is permanently secured by means of a fastening pin 22 extending diametrically through the shank 21 at its upper end. The shank 21 extends downwardly through an opening 20 provided in the bottom rail 17 and has attached to its projecting lower end an integral therewith a snap fastener head 23. A circumferential flange 24 of smaller diameter than the opening 20 projects horizontally from the shank 21 above the snap fastener head 23 and serves to engage and support a slat-supporting washer 26. The slat-supporting washer 26 having a center opening therein is slidably and detachably mounted on the shank 21, the under face of the washer engaging the flanged portion 24 of the shank 21 and the upper face of the washer engaging the surface of a recess 21 provided in the under side of the rail 17. As best seen in Fig. 8 the washer 26 has a central opening 25 providing a sliding fit over the shank 21 and also has a radial slot 28 cut through to the opening 25 which is narrow in at least one place than the diameter of the shank 21 so that the washer cannot be detached laterally from the shank but is wide enough to permit the cord 19 to be forced diametrically therethrough.

The lower ends of the individual tape members of the ladder tape 16 extend underneath the under side of the rail 17 where their extreme end portions are turned inwardly toward the rail and fastened together in a novel manner by a single stitching 29. One of the ends of the ladder tape 16 is longer than the other and extends underneath and across the bottom rail 17 to its other side where it is secured to the outer section of the tape which is shorter. If desired, only one of the tape ends may be doubled back upon itself and the other tape end may be disposed in overlapping relation therewith so that the end edges of the tapes are in alignment. Thus a single stitching suffices to secure them together and a neat seam is presented with no loose tape ends showing these ends being concealed against the bottom rail 17.

A center opening 15 is provided in the longer end section of the tape 16 over which is fitted a female or socket member 31 of a snap fastener. As shown clearly in Fig. 3, the detachable cord fastening device comprising the shank 21 having the snap fastener head 23 and the washer 26 accomplishes a three-fold purpose: (1) the cord 19 is secured to the bottom rail 17 for raising and lowering the blind, (2) the washer 26 supports the bottom rail 17, and (3) the snap fastener head 23 engages the socket member 31 thereby securing the ladder tape 16 to the under surface of the bottom rail 17 for tilting purposes.

and clamping the washer securely in position between the under surface of the recess 27 and the head 23.

In Figs. 4 to 7, a modified form of the detachable cord fastening device comprising the present invention for use in conjunction with a four-tape Venetian blind is shown wherein the cords terminate at the head rail. It is to be understood, however, that the modified form has application to a bottom rail and may be there utilized in a satisfactory manner. In the assembled view of the blind illustrated in Fig. 4, a tilting rail 40 is pivotally mounted beneath the head rail 41 and is connected with a tilting mechanism 42 for opening and closing the blind. Four ladder tapes 43, secured at their upper ends to the tilting rail 40, extend downwardly and are fastened at their lower ends to the bottom rail 44, the rungs of the ladder tapes providing lateral support for a plurality of horizontal slats 46. In this form of the device, however, the ends of the raising and lowering cord 47 extend from a looped operating portion 48 over a pulley 49, horizontally within the head rail 41 over a pair of upper pulleys 50 and 51, thence downwardly through a plurality of aligned openings (not shown) in the slats 46 to a pair of lower pulleys 52 and 53 disposed in the bottom rail 44, horizontally and outwardly along the bottom rail 44 to a pair of outer pulleys 54 and 55, thence upwardly through other aligned openings (not shown) in the slats 46, the ends of the cord 47 emerging above the tilting rail 40.

As shown more clearly in Fig. 5, each end of the operating cord 47 then extends through an eye 57 fastened to the under side of the head rail 41 and then horizontally to a second eye 58 also attached to the under side of the head rail 41. The eye 58 is similar to the washer 26 of Figs. 1 to 3, inclusive. The detachable cord fastening device in this case comprises an elongated tubular shank 59 permanently secured at one end to the ends of the raising and lowering cord 47 by means of crimped portions 55 serving the same purpose as the pin 22 of the embodiment shown in Fig. 3. The opposite end of the shank 59 is provided with a flange 60. The eye 58 has a central opening 61 of a diameter slightly greater than the diameter of the shank 59, providing a sliding fit therewith, and also slightly less than the diameter of the flange 60 whereby the shank 59 and its flange 60 are prevented from slipping through the opening of the eye 58. The eye 58 is provided with a radial opening or gap 62 which is narrower than the diameter of the shank 59 but wide enough to allow the cord 47 to be forced diametrically therethrough. The opening of the other eye 57 is of sufficient size to permit the shank 59 and its flange 60 to pass therethrough for assembly and attachment. The eye 57 is in alignment with the slot 63 and serves to change the direction of the cord 47 to the retaining washer eye 58, but it is apparent that it could be entirely eliminated and the washer eye 58 arranged horizontally, instead of vertically, in alignment with the slats in the slots.

In this form of the invention, the detachable cord fastener serves only to detachably secure the ends of the cord 47 to the blind and does not support the bottom rail 44 or secure the lower end of the ladder tapes 43 thereto as in the case of the device illustrated in Figs. 1 to 3. The lower ends of the individual tape members of the ladder tapes 43 are turned inwardly toward the rail and stitched as at 63 at the under side of

the rail 44 in the same manner as shown in Fig. 3. A snap fastener socket member 64 is fitted into a center opening 66 provided in the long ends of the tapes 43 and is adapted to engage a snap fastener head 67 of a screw 68 affixed to the under side of the bottom rail 17 as shown in Fig. 7.

By means of the detachable cord fastener of the present invention, the raising and lowering cords may be detached from the Venetian blind by a quick and simple operation requiring no tools and relatively slight mechanical ability. The detachable fasteners are in positions readily accessible to the operator and may be manipulated without discomfort or strain. In disassembling the blind shown in Figs. 1 to 3, inclusive, the snap fastener socket 31 is first disengaged from the snap fastener head 23 after which the ladder tape 16 may be displaced laterally to expose the recess 27. The bottom rail 17 is then raised a sufficient distance to permit the washer 26 to be moved longitudinally along the shank 21 onto the cord 19 at which point the washer may be removed entirely by forcing the cord 19 outwardly through the radial opening 23 in the washer. The supporting washer 26 having been removed, the cord 19 and the shank 21 may now be raised upwardly through the opening 20 in the rail 17 and the openings in the slats 18 to permit lateral removal of the latter for cleaning. The blind may be reassembled by reversing the above series of steps.

In the embodiment of the invention illustrated in Figs. 4 to 7, inclusive, the raising and lowering cord 47 is readily removed by sliding the shank 59 and cord 47 inwardly toward the center of the blind until the shank 59 has cleared the opening 61 in the eye 58. The cord is then forced diametrically through the radial opening 62. Thereafter, the cord 47 and shank 59 may be withdrawn through the larger eye 57 and through the openings in the slats 46 to permit removal of the slats. If it is desired to remove the bottom rail 44 also for cleaning, the snap fastener sockets 64 at the bottom of each ladder tape 43 may be disengaged from the snap fastener heads 67 to permit lateral removal of the rail 44. The blind may be reassembled by following the above steps in reverse order.

It will be understood that modifications and variations, other than the specific forms of the invention herein described, may be resorted to without departing from the scope of the invention as defined in the appended claims.

I claim:

1. A detachable cord fastening device for a Venetian blind comprising an elongated shank adapted to be secured at its upper portion to an end of a raising and lowering cord and to extend through a rail in supporting relation therewith, and a tape-securing means comprising a snap-fastener head on the lower end of said shank and a snap-fastener socket adapted to be secured in a tape for cooperation with said head whereby to detachably secure the cord and tape in place adjacent the rail.

2. In a Venetian blind structure, a horizontal rail having an opening therethrough to receive the end of a raising and lowering cord, an elongated shank secured at its upper portion to the end of said cord, a slat-supporting tape passing under said rail, and means for securing said tape to the end of said shank comprising a snap-fastener head on the lower end of the shank and a snap-fastener socket secured to said tape and adapted to receive said snap-fastener head for detachably securing the cord and tape in place adjacent the rail.

3. A detachable cord fastening device for a Venetian blind comprising an elongated shank adapted to be secured to an end of a raising and lowering cord and to extend through a rail in supporting relation therewith, means for holding said shank to prevent movement of the cord relative to the slats of the blind comprising a laterally directed projecting portion on said shank and a rail-supporting member detachably connected with said shank and having an interior opening in which said shank is axially slid able of lesser extent than said projecting portion and a radial opening extending from said interior opening to the marginal edge of the member, said radial opening being narrower than the thickness of said shank but wide enough to permit said cord to pass therethrough to said interior opening, and a tape-securing means comprising a snap fastener head on the lower end of said shank and a snap fastener socket adapted to be secured in a tape for cooperation with said head whereby to detachably secure the cord and tape in place adjacent the rail.

4. In a Venetian blind structure, a horizontal rail having an opening therethrough to receive the end of a raising and lowering cord, an elongated shank secured at its upper portion to the end of said cord, a slat-supporting tape passing under said rail, and means for securing said tape to the end of said shank comprising a tape-fastening element at the lower end of said shank and a complementary tape-fastening element secured in said tape, said complementary tape-fastening element being frictionally engageable with said first-named tape-fastening element for detachably securing the cord and tape in place adjacent the rail.

EDWARD E. SCHAEFER.
